HENRI FRENAY, OF LÜTTICH, AND HANS GRAEVE, OF HERSTAL, NEAR
LÜTTICH, BELGIUM.

REPEATING RIFLE.

No. 845,075.

Specification of Letters Patent.

Patented Feb. 26, 1907.

Application filed January 19, 1905. Serial No. 241,755.

To all whom it may concern:

Be it known that we, HENRI FRENAY, a subject of the King of Belgium, residing at 3 Rue Laport, Lüttich, Belgium, and HANS GRAEVE, a subject of the King of Prussia, residing at 8 Au Rivage, Herstal, near Lüttich, Belgium, have invented certain new and useful Improvements in Repeating Rifles, of which the following is a full, clear, and exact description.

This invention relates to repeating rifles or recoil-loaders in which the ordinary box-magazine is replaced by a magazine consisting of a tube which extends under the barrel.

The object of the invention is the construction of a magazine-stop for the type of repeating rifles referred to, the locking-lever of which fulfills not only its ordinary well-known function of preventing the outermost cartridge from leaving the magazine or of providing after having been put in position a counter-bearing for this cartridge, but which, moreover, when moved fulfills the important function of pressing back into the tube, against the pressure of the magazine-spring, the cartridge which under pressure of the magazine-spring projects beyond the mouth of the magazine. By being thus pressed back the cartridge is removed out of the reach of the carrier that lifts the cartridges into alignment with the barrel in such a manner that the weapon without interfering with the action of the carrier can be used as a single-loader—that is to say, the cartridges can be introduced into the barrel by hand.

The accompanying drawings illustrate the invention.

Figures 1 and 2 are a side view and a longitudinal horizontal section of parts of a repeating rifle provided with the new magazine-stop when out of engagement. Fig. 3 is a longitudinal horizontal section of parts of a repeating rifle, showing the new stop when in engagement; and Figs. 4 and 5 show, respectively, a side elevation and a plan of the lever-stop.

In the example illustrated the new magazine-stop is attached to a recoil-loader on the Browning system, the magazine of which consists of a tube under the barrel. It is formed by the lever-stop *s t*, which is placed behind the outlet of the tube *m* of the magazine and is mounted in the side wall of the frame *g* of the lock in such a manner as to be

able to oscillate horizontally around a pin *u*. 55 The lever-stop is held rigidly in its most extreme positions by a spring *v*, which prevents it from being accidentally turned. The inner arm *t* of this two-armed lever-stop extends nearly as far as the mouth of the tube 60 forming the magazine, and, acting in opposition to the action of the follower which pushes the cartridges out of the magazine, removes, when adjusted in the locking position, Fig. 3, the outermost cartridge *p* out of 65 the reach of the carrier *z*. The outer arm *s* of the lever-stop is provided with a handle which extends sufficiently beyond the side of the frame *g* of the lock to be conveniently actuated by hand. 70

When the lever is out of engagement, the position of the arm *t* is such as to bring it in line with the inner surface of the frame of the lock, and consequently there is space for the cartridges to pass freely. 75

What we claim as our invention, and desire to secure by patent, is—

1. In a repeating firearm, a device for moving the cartridge which is adjacent to the magazine-mouth in a direction reverse to the 80 direction of the feed, and for mechanically holding the cartridge in such position.

2. In a repeating firearm, a carrier, a magazine having means for moving a cartridge into position to be engaged by said carrier, 85 and a manually-operable device for moving such cartridge out of such position, whereby the carrier is prevented from feeding cartridges from the magazine and the firearm is adapted for hand-loading. 90

3. In a repeating firearm, a carrier, a magazine having means for moving a cartridge into the sphere of action of said carrier, and a device for preventing the action of such means, said device adapted to move the cartridge out of such position. 95

4. In a firearm, a carrier, a magazine having means for moving a cartridge into the sphere of action of said carrier, means for moving said carrier to bring the cartridge to 100 firing position, mechanism for moving such carrier and firing the cartridge, such mechanism adapted to permit said firearm to be loaded by hand, and a device for moving such cartridge out of the sphere of action of 105 said carrier, whereby to cause the latter to remain inoperative when the firearm is to be loaded by hand.

5. In a repeating firearm, a carrier, a magazine having means for moving a cartridge into position to be engaged by said carrier, and a manually-operable device for moving such cartridge out of such position, whereby to adapt the firearm for hand-loading, such device comprising a two-armed lever adapted to move horizontally to push the cartridge backwardly out of such position.
10. 6. In a firearm, a carrier, a tubular magazine, means for pushing the cartridges rearwardly therein, a two-armed lever arranged at the breech and adapted in one position to

permit the carrier to act to feed the cartridge from such magazine, and in another position to hold the cartridges in a position out of the sphere of action of such carrier, whereby to adapt such firearm for hand-loading. 15

In witness whereof we have hereunto signed our names in the presence of two sub- 20 scribing witnesses.

HENRI FRENAY.
HANS GRAEVE.
